SALAD BOWL OR THE LIKE

Arnold Alder Blanch, Woodstock, N. Y., assignor
to Castleton China Incorporated, New York,
N. Y., a corporation of New York

Application November 2, 1949, Serial No. 5,828

Term of patent 14 years

(Cl. D44—15)

To all whom it may concern:

Be it known that I, Arnold Alder Blanch, a citizen of the United States of America, residing at Woodstock, in the county of Ulster and State of New York, have invented a new, original, and ornamental Design for a Salad Bowl or the like, of which the following is a specification, reference being had to the accompanying drawing, forming part thereof.

In the drawing:

Fig. 1 is a top plan view of a salad bowl, showing my new design; and

Fig. 2 is a side elevational view thereof.

I claim:
The ornamental design for a salad bowl or the like, as shown.

ARNOLD ALDER BLANCH.
